UNITED STATES PATENT OFFICE.

HELEN E. DOWNS, OF LOS ANGELES, CALIFORNIA.

HAIR CLAMP.

Application filed January 23, 1928. Serial No. 248,691.

This invention relates to improvements in hair clamps and has for its object to provide a simple cheap and efficient device for clamping the hair in a curl or twisted position in order to form curls or waves in the hair.

The invention consists of the novel construction and arrangement of the parts and combination of the parts hereinafter more fully set forth in the following specification and pointed out in detail in the appended claims.

In the accompanying drawing:

Figure 1 is a side elevation of my invention in the closed position.

Figure 2 is a similar view of Figure 1 showing the opposite end thereof.

Figure 3 is a top plan view of Figure 1.

Figure 4 is a side elevation showing the resilient jaws open and the retainer in the raised position.

Figure 5 is a top plan view with the resilient jaws apart.

Figure 6 is a similar view of Figure 2 with the retainer in the raised position.

Referring to the accompanying drawings forming part of this specification and in which like reference numerals designate like parts throughout the several views thereof, 1 and 2 designate the resilient jaws which are normally apart and which are integral with

and extending from the cylindrical end 3. These jaws 1 and 2 are normally apart as shown in Figure 5. The jaw 2 has a cylindrical retainer 4 pivoted thereto at 5. On one side of said retainer 4 is an outwardly projecting curved lip 6 which extends over the end of the jaw 1 and draws the latter in close to the jaw 2 when the retainer is forced down to the position shown in Figure 1.

When it is desired to operate the device the retainer 4 is raised allowing the jaws 1 and 2 to spring apart. The hair which is curled or twisted is placed between the jaws 1 and 2 and the latter forced together and held tightly by the retainer 4. The clamp is allowed to remain on the hair for the desired length of time after which it is removed leaving the hair curled or waved.

Having thus described my invention what I claim is:

A hair clamp comprising a cylinder at one end and two integral resilient jaws projecting from said cylindrical end and having their free ends normally apart, a retainer pivoted to one of said jaws and having an outwardly projecting curved lip at one end adapted to project over the jaws and draw them into the closed position.

In testimony whereof I affix my signature.

HELEN E. DOWNS.
